(57) **CLAIM**

The ornamental design for an illuminated sign, as shown and described.

DESCRIPTION

FIG. 1 is a front perspective view of the illuminated sign according to the present design;

FIG. 2 is a front elevational view of the illuminated sign of FIG. 1;

FIG. 3 is a rear elevational view of the illuminated sign of FIG. 1;

FIG. 4 is a right-side elevational view of the illuminated sign of FIG. 1, the left-side elevational view being a mirror image thereof;

FIG. 5 is a top plan view of the illuminated sign of FIG. 1;

FIG. 6 is a bottom plan view of the illuminated sign of FIG. 1; and,

FIG. 7 is a front perspective view of the illuminated sign of FIG. 1, showing the illuminated sign in a manner of use. In the drawings, the broken lines depict portions of the illuminated sign that form no part of the claimed design.

1 Claim, 6 Drawing Sheets
